United States Patent Office

Des. 233,627

Patented Nov. 12, 1974

233,627

TOOLHOLDER

George A. Waddell, 35 S. Groesbeck Highway, Apt. 161,
Mount Clemens, Mich. 48043

Filed Feb. 26, 1973, Ser. No. 335,457

Term of patent 14 years

Int. Cl. D15—09

U.S. Cl. D54—6

FIG. 1 is a perspective view of a toolholder showing my new design;

FIG. 2 is a top view thereof;

FIG. 3 is a bottom view thereof;

FIG. 4 is a rear view thereof;

FIG. 5 is a front view thereof;

FIG. 6 is a left side view thereof; and

FIG. 7 is a right side view thereof.

I claim:

The ornamental design for a toolholder, as shown and described.
